[57] CLAIM

The ornamental design for a shower bar, as shown and described.

DESCRIPTION

FIG. 1 is a perspective view of a shower bar, showing my new design;

FIG. 2 is a top plan view thereof, the bottom view being a mirror image thereof;

FIG. 3 is a front elevational view thereof;

FIG. 4 is a right side elevational view thereof, the left side being a mirror image thereof; and,

FIG. 5 is a rear elevational view thereof.

The broken line showing is for illustrative purposes only and forms no part of the claimed design.
